UNITED STATES PATENT OFFICE

EDWARD L. ACKERMAN, OF DETROIT, MICHIGAN, ASSIGNOR TO ACKERMAN-BLAESSER-FEZZEY, INC., OF DETROIT, MICHIGAN, A CORPORATION OF MICHIGAN

SUPPORTING FRAME FOR WINDOW-REGULATOR MECHANISM

Application filed March 23, 1928. Serial No. 264,121.

This invention relates to window regulators and the object of the invention is to provide a window regulator including a frame member for the door with which the regulator is utilized, the frame member and regulator being formed integrally.

Another object of the invention is to provide a frame member on which the different parts of the window regulator are mounted, the frame member forming part of the regulator.

A further object of the invention is to provide a window regulator including a door frame member forming a support for the different parts of the window regulator mechanism which are mounted thereon.

These objects and the several novel features of the invention are hereinafter more fully described and claimed and the preferred form of construction by which these objects are attained is shown in the accompanying drawings in which—

Fig. 1 is a front elevation of a window regulator and frame embodying my invention.

Fig. 2 is a rear elevation thereof.

Fig. 3 is an enlarged section taken on line 3—3 of Fig. 2.

Fig. 4 is a section taken on line 4—4 of Fig. 2.

Fig. 5 is a perspective view of the rear side of the frame member on which the regulator mechanism is mounted.

The device comprises a frame member 1 which is adapted to be secured across the door frame in an automobile body by means of screws inserted through the apertures 2 shown in Fig. 1 and threaded into the adjacent door frame. The frame member 1 is provided with strengthening ribs 3 formed therein intermediate its ends to stiffen the sheet metal frame member. This frame member 1 is provided with an inturned upper edge or strengthening flange 4 and is also provided with a depending portion 5 shown in Figs. 1, 2 and 5. In forming this frame member an arcuate slot 6 is cut through the metal and the portion 5 of the metal is offset to one side of the plane of the frame member as will be understood from Figs. 3 and 5 so that the por-

tion above the slot 6 forms a depending lip spaced from the metal surface of the offset portion 5. The lower edge of the frame member including the depending portion 5 is provided with an inturned flange or edge 7 which stiffens the lower edge of the metal frame member and depending portion. A rotatable member 8 is provided as shown in Figs. 3 and 4 having cylindrical portions 9 rotatably mounted in the depending portion 5 and in the housing 10 secured thereto. The housing 10, as will be understood from Figs. 1, 3 and 4, is provided with four extending lugs 11 which extend through apertures in the depending portion 5 and are peened over to hold them in place. This housing 10 combines with the depending frame portions 5 to provide a chamber in which the counter balancing spring 12 is entirely enclosed. One end of this spring is secured in the slot 13 in the member 8 and the opposite end of the spring is provided with a hook end 14 engaging in an aperture in the housing 10. The member 8, which is rotatably mounted in the housing 10 and portion 5, is provided with

flattened portions 15 on the ends and a gear segment 16 is secured to one end 15 while a regulator arm 17 is secured to the opposite end 15. By this arrangement when the member 8 is rotated in the stationary housing members 5 and 10 the gear segment 16 and arm 17 are rotated therewith. The arm 17 is provided with an enlarged hub having an arcuate recess 30 shown in Figs. 2 and 4 and the housing 10 is provided with a struck up lug 31

riding in the recess 30 and limiting turning movement of the arm 17 in either direction. The gear segment 16, as will be understood from Figs. 1 and 2, extends beneath the lip 6 and meshes with the gear 18. As shown in Figs. 3 and 5 the depending portion 5 is provided with an arcuate rib 19 against which the gear segment 16 rides and an annular rib 20 is provided in this portion to space the gear segment from the depressed portion 5 and to reduce the friction between these two members. The housing 10 is also provided with an annular rib 21 to reduce the friction between the rotatable arm 17 and the housing 10. The spring 12 tends to raise the arm 17

and thus counter balances the weight of the sash supported by this arm. At the upper end the arm 17 is provided with a roller 22 riding in a metal way 23 secured to the lower edge of the sash and by this connection the turning of the arm 17 raises and lowers the sash. The gear 18 is rotatably mounted on a shaft 24 which extends through the extruded opening 25 in the frame member 1 and a housing 26 is secured to this frame member as shown in Figs. 1, 3 and 5 by means of the three apertures 27 provided therefor. This housing contains a coiled spring 28 which normally is extended into tight engagement with the wall of the housing 26 and locks the gear 18 from rotative movement. This construction is subject matter of a separate application about to be filed, and provides an arrangement for locking the gear 18 against movement by the arm 17 and gear segment 16. This device is arranged so that a crank may be attached to the end 29 of the shaft 24 and upon rotation of this crank and shaft in either direction the coiled spring is contracted and allows rotation of the shaft 24 and gear 18 to raise or lower the sash. Turning movement of the gear 18 by movement of the gear segment 16 however causes expansion of the spring 28 into tight engagement with the wall of the housing thus preventing rotation of the gear 18 in either direction. This device, however, forms no part of the present invention.

The lower end of the housing 26 is provided with a flange 29 and the gear segment 16 moves between this flange and the depending lip 6 of the frame member 1. The flange 7, as will be noted from Fig. 5, provides a stiffening connection between the depending end 5 and the body portion of the frame member so that while the portion 5 is depressed it is still connected to the member 1 with sufficient strength to properly support the parts of the window regulator. The frame member 1 together with the parts of the window regulator may be positioned on a door frame of an automobile body and secured in position by means of screws threaded through the aperture 2 and thus the entire regulator assembly may be secured in place as a unit.

From the foregoing description it becomes evident that the device is simple and efficient in operation, reduces the assembly labor on an automobile body and provides a device which accomplishes the objects described.

Having thus fully described my invention, its utility and mode of operation, what I claim and desire to secure by Letters Patent of the United States is—

1. A supporting frame for a window regulator mechanism, comprising a metal plate having a portion at its lower edge offset to one side of the surface of the remainder thereof, the lower edge of the frame member and offset portion being provided with a periph-

eral strengthening flange, said frame member having a slot opening through the edge of the offset portion, a housing secured to the offset portion and forming therewith a chamber for a part of the regulator mechanism to which the regulator arm is attached, said housing having a struck up-lug positioned to limit rotative movement of the regulator arm in either direction, and an operating means for said arm supported by the frame member above the offset portion.

2. A supporting frame for a window regulator mechanism, comprising a sheet metal plate having a depending portion at its lower edge offset to one side of the plane thereof, a continuous flange extending along the lower edge of the frame and about the edge of the depending offset portion, the plate having a slot opening through the edge of the offset portion, a sheet metal housing secured to the offset portion within the flange and with the said offset portion providing a chamber, said housing on the side opposite the offset portion having outpressed parts and the depending portion forming the opposite side thereof likewise having outpressed parts for the purpose described, said plate further having strengthening ribs formed therein.

3. A supporting frame for a window regulator mechanism, comprising a sheet metal plate having a depending portion at its lower edge offset to one side of the plane of the plate, there being a slot through the edge of the offset portion at its point of engagement with the plate providing a depending lip extending downwardly in the plane of the frame member, said offset portion having the metal thereof struck up outwardly from the surface to form a bearing for a regulator element and a housing secured to the offset portion likewise having the metal thereof struck up outwardly providing a bearing surface for a window operating element, and means supported by the plate for operating the same.

In testimony whereof, I sign this specification.

EDWARD L. ACKERMAN.
